UNITED STATES PATENT OFFICE.

EDSON O. SESSIONS, OF CHICAGO, ILLINOIS, ASSIGNOR OF ONE-HALF TO R. JARVIS GAUDY, OF CHICAGO, ILLINOIS.

LOCKING-SWITCH.

1,366,504.

Specification of Letters Patent. Patented Jan. 25, 1921.

Application filed April 8, 1918. Serial No. 227,200.

To all whom it may concern:

Be it known that I, EDSON O. SESSIONS, a citizen of the United States, residing at Chicago, in the county of Cook and State of Illinois, have invented a certain new and useful Improvement in Locking-Switches, of which the following is a specification.

My invention relates to an improved type of locking switches for use particularly with alternating currents where high amperages are possible. Heretofore in the art, devices have been employed for retaining an operating tool in engagement with the switch blade, or a part carried thereby, during the time that a pull is exerted upon the switch blade in opening the same, or a thrust exerted on the tool in closing the switch. With these devices, however, it is possible to remove the operating tool at any time from the locking devices by ceasing to exert a longitudinal force on the operating tool, which permits the removal of the tool from the switch blade, or part carried thereby, to receive said tool. Other devices have been employed in connection with locking switches, supported from the base of the switch to retain the operating tool in engagement with the switch blade until the latter has been opened a desired amount, depending upon the formation and proportion of the retaining devices, after which the tool may be removed from the switch blade, even though the latter is not moved to its fully opened position. In other words, with one class of these locking devices, the pull or thrust upon the operating tool controls whether the latter is retained against removal from the switch blade, and in the other class of devices, mechanism carried by the base of the switch controls the insertion or removal of the tool from the switch blade. By my invention I retain the operating tool in engagement with the switch blade by means independent of the base of the switch and independent of the exertion of a pull, or thrust, upon the operating tool, which means are mounted upon the switch blade itself and may be made to retain the operating tool in place in the locking mechanism for any desired angle of rotation of the switch blade, with the result that after the switch blade has been moved through said angle, the operating tool may be removed readily from the locking devices.

Furthermore, by my construction, the tool retaining means is operative during the closure of the switch blade to retain the tool in engagement with the locking devices until the locking mechanism is in a locking position to retain the switch blade in its closed position, all of which is accomplished by devices mounted upon the switch blade.

My invention will best be understood by reference to the accompanying drawings, showing preferred embodiments thereof, in which—

Figure 1. shows a complete switch in side elevation with an operating tool in engagement with the locking devices.

Fig. 2. is a detail view of the operating end of the operating tool.

Fig. 3. is an enlarged view in side elevation of the locking mechanism.

Fig. 4. is a top view of the parts shown in Fig. 3.

Fig. 5. shows in a sectional view similar to Fig. 3, the inside construction of the locking mechanism.

Fig. 6. is a sectional view of the parts shown in Fig. 5, taken along the line 6—6.

Fig. 7. shows in a view similar to Fig. 3 a construction of locking mechanism having a modified form of opening for receiving the operating tool.

Fig. 8 shows in a view similar to Fig. 3, a modified form of locking devices.

Fig. 9 is a top view of the parts shown in Fig. 8, and

Fig. 10 shows a modified form of operating tool.

Similar numerals refer to similar parts throughout the several views.

The detail construction of the locking mechanism will best be understood by reference to Figs. 5 and 6, and as shown in said figures, the switch blade 10 is in closed position in the contact clip 11, which clip is supported from a base 12, upon which the bracket 13 is secured by screws 14. A catch 15 is pivotally connected to the bracket 13 at 16 and held in the position indicated by a spring 17. A projection 15^a rests against the face of the base 12 under the action of the spring 17 to prevent the catch moving beyond the position indicated. The catch 15 is of double construction as indicated in Fig. 6, consisting really of two parts similarly conformed and held a proper distance

apart by a spacing rod 18, against which one end of the spring 17 rests. The catches 15 are made to be engaged by hooks 19 projecting from disks 20, disposed upon opposite sides of a bracket 21, secured by rivets or bolts to the end of the switch blade 10. Between the disks 20, the bracket 21 is provided with a circular hole extending therethrough of a diameter somewhat less than the diameter of the disks 20, and the disks are provided with grooves 20a in their inner faces to engage the opposite ends of the hole through the bracket 21, as a result of which the disks enter the hole somewhat and may 5 rotate in the hole upon the bracket. A filler or sleeve 22 of smaller external diameter than the diameter of said hole, is disposed between the disks 20 and said disks and filler are secured together by rivets 23 extending through them. The filler 22 may be replaced, if desired, by a projection or projections from the disks 20. An aperture 24 is formed centrally through the disks 20 and the filler 22 to receive the head of the operating tool, and while this aperture may be given a variety of conformations, that shown in Figs. 5 and 6 is hexagonal as this shape is found to serve the purpose admirably. 10 In the space between the outer surface of the filler 22 and the bracket 21, a spiral spring 25 is disposed, one end of which is secured by rivets to the filler 22, while the other end is similarly secured to the bracket 25 21 in such a manner that there is a tendency at all times to rotate the disks 20 and the hooks 19, carried thereby, in a clockwise direction for the arrangement of parts shown in Fig. 5, this tendency being the greatest 30 when the hooks are in engagement with the catches 15. The bracket 21 has projecting from its upper edge, oppositely disposed lugs 26 extending over the edges of the oppositely disposed disks 20, which disks are 35 provided with projecting lugs 27 for engaging the lugs 26 when the switch blade is in its fully opened position. 40 As indicated in Fig. 1, the switch blade 10 is pivotally mounted at 28 on the pivot clip 50 29, held in proper relation to the contact clip 11 by a support 30. With the parts in the position indicated in Figs. 1 and 5, the operating head 31 of the tool 32, shown in Fig. 2, may readily be inserted in the hole 24 55 since the conformation of the notches in the catches 15 prevents the spring 25 from rotating the hooks 19 beyond the position indicated in said figures. After the operating tool is inserted in the aperture 24, it is 60 moved downwardly to a position indicated by the broken line $a-a$, which rotates the hooks 19 from engagement with the catches 15 after which they may be moved with the switch blade 10 relatively to the contact clip 65 11. For this position $a-a$ of the operating

tool, a pull thereon moves the switch blade from engagement with the contact clip and opens the switch, but since the hooks 19 are clear of the catches 15 and are not prevented from rotating in the bracket 21, except by 70 the operating tool 32, the total force of the spring 25 is exerted upon the head 31 of the operating tool, thus preventing movement of the head in the aperture 24. This condition continues until the switch blade 75 10 is moved to its fully opened position, which may be taken as a horizontal position for the arrangement shown in Fig. 1, at which time the lugs 27 come into engagement with the lugs 26, and thus further rotation of the hooks 19, relatively to the bracket 21, is prevented and the operating tool may be freely removed from the aperture 24. 80

From the above, it will be observed that 85 during the entire operation of opening the switch blade, the operating tool is effectively held in engagement with the locking devices and cannot readily be removed therefrom, thus requiring the complete opening 90 of the switch in order to remove the operating tool. Furthermore any amount of angular motion of the switch blade may be required before rotation of the hooks 19 relatively to the bracket 21 is prevented by 95 the lugs referred to to release the operating tool; for certain conditions, if desired, it may be necessary to move the switch blade through 180 degrees, instead of 90 degrees, to release the operating tool. Similarly, in 100 closing the switch, it will be observed that the parts are left in a position such that the operating head 31, of the operating tool, readily enters the aperture 24, and that from the time the closing operation is started 105 the full force of the spring 25 is exerted upon the operating head of the tool, which continues until the hooks 19 are properly seated in the notches in the catches 15. If it is attempted to release the operating tool before the switch blade 10 is moved to its 110 fully closed position, and the operating tool is swung in the bracket 21 to move the hooks 19 into engagement with the catches 15, the ends of the hooks engage the ends of the catches and move said catches upon their pivot 16 against the action of the spring 17. This permits rotation of the hooks 19 to retain the operating tool firmly in engagement with the locking mechanism, and 115 since the catches 15 are designed to clear the hooks 19 for this condition, and not prevent continued rotation of said hooks, the operating tool cannot be removed from the locking mechanism, except by again rotating the hooks 19 to a position permitting the catches 15 to return to the position indicated in Figs. 1 and 5. Then after wholly 120 closing the switch blade, raising the operating tool sufficiently to permit the hooks to 125 130

properly seat in the notches formed therefor in the catches 15, for which relation the engagement of the edges of the hooks with the side walls of the notches in the catches 15, locks the hooks against rotation under the action of the spring 25 and the operating tool may be readily removed from the locking mechanism.

If desired the head of the operating tool 10 may be constructed as shown at 33 in Fig. 10, in which construction the body portion of the said head is somewhat smaller than the aperture 24, although of the same general cross-section, and said head 15 is provided at its outer end with a flange 34 of a size and conformation to just clear the aperture 24 when the tool is placed in engagement with the lock mechanism of the switch. The result of this is 20 that the flange 34 renders the removal of the tool from the locking mechanism impossible during the interval that the force of the spring 25 is exerted on the tool, owing to the interlocking relation of the flange 34 25 with one of the disks 20. In other respects the operating tool 35 shown in Fig. 10 is similar to the operating tool 32 and operates the locking mechanism in the same manner as described above.

30 The aperture provided in the locking mechanism to receive the operating tool may have any desired conformation, as long as it prevents rotation in the locking hooks of the similarly conformed head of the operating tool. As shown in Fig. 7 the construction of locking mechanism carried by the switch blade 10^a is the same as above described, with the exception that the aperture 24^a is of an irregular outline composed 35 of curved surfaces related to each other in a manner to prevent rotation therein of an operating tool having a head similarly conformed.

The construction shown in Figs. 8 and 9 40 is similar to that above described, the principal differences being in the construction of the catches employed to engage the locking hooks. In this construction the switch blade 10^b is provided with locking hooks 19^b 45 extending from disks 20^b mounted on the end of the switch blade in substantially the manner above described. The hooks 19^b are arranged to engage a rod 36 when the switch blade is in its wholly closed position, which 50 rod is supported by the lower end of the link 37, the upper end of which is pivotally mounted on a rod 38 carried by a bracket 39 secured to the base 12^b on the contact clip 11^b. An extension 39^a on the bracket 39 55 prevents the rod 36 moving outwardly beyond the position indicated in Fig. 8, in which position said rod is normally held by a spring 40. With the construction described, if the operating tool is moved angularly relatively to the switch blade 10^b

after the switch blade 10^b is in engagement with the contact clip 11^b and moved nearly to its fully closed position, the ends of the hooks 19^b engage the top of the rod 36 and rotation of the hooks presses the rod downward and to the right so that the action of the spring in the bracket 21^b continues to be exerted on the head of the operating tool and to release the operating tool it is necessary to again raise the hooks 19^b and move 70 the switch blade 10^b to its fully closed position before again permitting the hooks 19^b to rotate to engage the rod 36, for which condition the engagement of the hooks with the rod locks the hooks against rotation and 75 releases the operating tool so that it may be withdrawn. In other respects the construction of the locking mechanism shown in Figs. 8 and 9 is the same as that above described.

80 From the above it will appear that by my invention I provide a locking mechanism for switches in which the only projecting parts of the locking mechanism carried by the switch blade are the locking hooks, and that by means of the locking mechanism carried by the switch blade, without the use of auxiliary devices, the operating tool may be positively retained in engagement with the locking mechanism 85 for any desired degree of angular movement of the switch blade upon its pivot before the operating tool can be released from the locking mechanism and removed from the switch, and that once the opening or closing 90 movement of the switch is begun, its full movement either to open or close the switch, as the case may be, must be completed before the operating tool can be removed from the switch.

95 While I have shown my invention in the particular embodiments above described, I do not limit myself to these exact constructions as I may employ equivalents thereof known to the art at the time of the filing of 100 this application without departing from the scope of appended claims.

105 What I claim is:

1. In a locking switch, the combination of a pivot clip, a contact clip, a switch blade pivoted to said pivot clip for engaging said contact clip, locking devices carried by said switch blade having a conformation to receive an operating tool, means carried by said switch blade for retaining an operating tool in engagement with said locking devices independently of a thrust or pull on the operating tool, and a catch mechanism pivotally mounted adjacent said contact clip for engaging said devices in the closed position of said switch blade to lock the switch blade in its closed position.

120 2. In a locking switch, the combination of a pivot clip, a contact clip, a switch blade 125

130

1 pivoted to said pivot clip for engaging said contact clip, locking devices carried by said switch blade having a conformation to receive an operating tool, said conformation 5 preventing longitudinal motion of said operating tool relatively to said locking devices, means carried by said switch blade for retaining the operating tool in engagement with said locking devices for a desired 10 angular movement of said switch blade, and a catch mechanism pivotally mounted adjacent said contact clip for engaging said devices in the closed position of said switch blade to lock the switch blade in its closed 15 position.

3. In a locking switch, the combination of a pivot clip, a contact clip, a switch blade pivoted to said pivot clip for engaging said contact clip, locking devices carried by said 20 switch blade having a conformation to receive an operating tool, means carried by said switch blade for retaining an operating tool in engagement with said locking devices independently of a thrust or pull on 25 the operating tool, and catch mechanism pivotally mounted adjacent said contact clip for engaging said devices in the closed position of said switch blade to lock the switch blade in its closed position and releasing the operating tool.

4. In a locking switch, the combination of a pivot clip, a contact clip, a switch blade pivoted to said pivot clip for engaging said contact clip, locking devices carried by said 35 switch blade having a conformation to receive an operating tool, said conformation preventing longitudinal motion of said operating tool relatively to said locking devices, means carried by said switch blade 40 for retaining the operating tool in engagement with said locking devices for a desired angular movement of said switch blade, and a catch mechanism pivotally mounted adjacent said contact clip for engaging said devices in the closed position of 45 said switch blade to lock the switch blade in its closed position and releasing the operating tool.

5. In a locking switch, the combination of a pivot clip, a contact clip, a switch blade pivoted to said pivot clip for engaging said contact clip, a locking hook pivotally connected to said switch blade and having an aperture through its body portion to receive 55 an operating tool, said aperture being conformed to prevent rotation of said tool in said body portion, a spring carried by said switch blade tending to rotate said locking hook relatively to said switch blade and 60 stops carried by said switch blade and body portion for preventing excessive rotation of said hook.

6. In a locking switch, the combination of a pivot clip, a contact clip, a switch blade 65 pivoted to said pivot clip for engaging said

contact clip, a locking hook pivotally connected to said switch blade and having an aperture through its body portion to receive an operating tool, said aperture being conformed to prevent rotation of said tool in 70 said body portion, a spring carried by said switch blade tending to rotate said locking hook relatively to said switch blade, stops carried by said switch blade and body portion for preventing excessive rotation of 75 said hook, and catch mechanism adjacent said contact clip engaging said hook to hold said switch blade in its closed position.

7. In a locking switch, the combination of a pivot clip, a contact clip, a switch blade 80 pivoted to said pivot clip for engaging said contact clip, a locking hook pivotally connected to said switch blade and having an aperture through its body portion to receive an operating tool, said aperture being conformed to prevent rotation of said tool in 85 said body portion, a spring carried by said switch blade tending to rotate said locking hook relatively to said switch blade, stops carried by said switch blade and body portion for preventing excessive rotation of 90 said hook, catch mechanism adjacent said contact clip engaging said hook to hold said switch blade in its closed position and to prevent rotation of said hook relatively to said 95 switch blade.

8. In a locking switch, the combination of a pivot clip, a contact clip, a switch blade pivoted to said pivot clip for engaging said contact clip, a locking hook pivotally connected to said switch blade and having an aperture through its body portion to receive an operating tool, said aperture being conformed to prevent rotation of said tool in 100 said body portion, a spring carried by said switch blade tending to rotate said locking hook relatively to said switch blade, stops carried by said switch blade and body portion for preventing excessive rotation of 105 said hook, and a catch pivotally supported adjacent said contact clip for engaging said locking hook in the closed position of said switch blade to lock said switch blade in its closed position.

9. In a locking switch, the combination of 115 a pivot clip, a contact clip, a switch blade pivoted to said pivot clip for engaging said contact clip, a locking hook pivotally connected to said switch blade and having an aperture through its body portion to receive 120 an operating tool, said aperture being conformed to prevent rotation of said tool in said body portion, a spring carried by said switch blade tending to rotate said locking hook relatively to said switch blade, stops 125 carried by said switch blade and body portion for preventing excessive rotation of said hook, and a catch pivotally supported adjacent said contact clip for engaging said locking hook in the closed position of said 130

switch blade to lock said switch blade in its closed position, the locking surfaces of said catch and locking hook cooperating by their engagement to prevent rotation of said locking hook relatively to said switch blade.

10. In a locking switch, the combination of a pivot clip, a contact clip, a switch blade pivoted to said pivot clip for engaging said contact clip, a locking hook pivotally connected to said switch blade and having an aperture through its body portion to receive an operating tool, said aperture being conformed to prevent rotation of said tool in said body portion, a spring carried by said switch blade tending to rotate said locking hook relatively to said switch blade, stops carried by said switch blade and body portion for preventing excessive rotation of said hook, and a catch pivotally supported adjacent said contact clip for engaging said locking hook in the closed position of said switch blade to lock said switch blade in its closed position, the locking surfaces of said catch and locking hook coöoperating by their engagement to prevent rotation of said locking hook relatively to said switch blade, the pivot of said catch being so disposed that engagement of said locking hook with said catch outside of said locking surface, moves said catch upon its pivot and permits rotation of said locking hook relatively to said switch blade.
11. In a locking switch, the combination of a pivot clip, a contact clip, a switch blade pivoted to said pivot clip for engaging said contact clip, a bracket carried by the free end of said switch blade, a sleeve extending through said bracket and having an internal conformation for receiving an operating tool and preventing rotation of said tool relatively to said sleeve, a spring disposed between said sleeve and said bracket, and a locking hook carried by said sleeve for locking the switch blade in its closed position.
12. In a locking switch, the combination of a pivot clip, a contact clip, a switch blade pivoted to said pivot clip for engaging said contact clip, a bracket carried by the free end of said switch blade, a sleeve extending through said bracket and having an internal conformation for receiving an operating tool and preventing rotation of said tool relatively to said sleeve, a spring disposed between said sleeve and said bracket, a locking hook carried by said sleeve for locking the switch blade in its closed position, and stops carried by the bracket and sleeve for preventing rotation of said sleeve under the action of said spring in the open position of said switch blade.
13. In a locking switch, the combination of a pivot clip, a contact clip, a switch blade pivoted to said pivot clip for engaging said contact clip, a bracket carried by the free end of said switch blade, a sleeve extending

through said bracket and having an internal conformation for receiving an operating tool and preventing rotation of said tool relatively to said sleeve, a spring disposed between said sleeve and said bracket, and a locking hook carried by each end of said sleeve for locking the switch blade in its closed position.

14. In a locking switch, the combination of a pivot clip, a contact clip, a switch blade pivoted to said pivot clip for engaging said contact clip, a bracket carried by the free end of said switch blade, a sleeve extending through said bracket and having an internal conformation for receiving an operating tool and preventing rotation of said tool relatively to said sleeve, a spring disposed between said sleeve and said bracket, a locking hook carried by each end of said sleeve for locking the switch blade in its closed position, and stops carried by the bracket and sleeve for preventing rotation of said sleeve under the action of said spring in the open position of said switch blade.

15. In a locking switch, the combination of a pivot clip, a contact clip, a switch blade pivoted to said pivot clip for engaging said contact clip, a bracket carried by the free end of said switch blade, a sleeve extending through said bracket and having an internal conformation for receiving an operating tool and preventing rotation of said tool relatively to said sleeve, a spring disposed between said sleeve and said bracket, a locking hook carried by said sleeve for locking the switch blade in its closed position, and a catch pivotally supported adjacent the contact clip to engage the locking hook in the closed position of the switch blade, the engaging surfaces of said catch and locking hook being conformed to prevent rotation of said catch and locking hook.

16. In a locking switch, the combination of a pivot clip, a contact clip, a switch blade pivoted to said pivot clip for engaging said contact clip, a bracket carried by the free end of said switch blade, a sleeve extending through said bracket and having an internal conformation for receiving an operating tool and preventing rotation of said tool relatively to said sleeve, a spring disposed between said sleeve and bracket, a locking hook carried by said sleeve for locking the switch blade in its closed position, stops carried by the bracket and sleeve for preventing rotation of said sleeve under the action of said spring in the open position of said switch blade, and a catch pivotally supported adjacent the contact clip to engage the locking hook in the closed position of the switch blade, the engaging surfaces of said catch and locking hook being conformed to prevent rotation of said catch and locking hook.

17. In a locking switch, the combination

6
of a pivot clip, a contact clip, a switch blade pivoted to said pivot clip for engaging said contact clip, a bracket carried by the free end of said switch blade, a sleeve extending through said bracket and having an internal conformation for receiving an operating tool and preventing rotation of said tool relatively to said sleeve, a spring disposed between said sleeve and said bracket, a locking hook carried by each end of said sleeve for locking the switch blade in its closed position, and catch mechanism pivotally supported adjacent the contact clip for engaging the locking hooks in the closed position of the switch blade, the engaging surfaces of said catch mechanism and locking hooks preventing rotation of said catch mechanism and said locking hooks.

18. In a locking switch, the combination of a pivot clip, a contact clip, a switch blade pivoted to said pivot clip for engaging said contact clip, a bracket carried by the free end of said switch blade, a sleeve extending through said bracket and having an internal conformation for receiving an operating tool and preventing rotation of said tool relatively to said sleeve, a spring disposed between said sleeve and said bracket, a locking hook carried by each end of said sleeve for locking the switch blade in its closed position, stops carried by the bracket and sleeve for preventing rotation of said sleeve under the action of said spring in the open position of said switch blade, and catch mechanism pivotally supported adjacent the contact clip for engaging the locking hooks in the closed position of the switch blade, the engaging surfaces of said catch mechanism and locking hooks preventing rotation of said catch mechanism and said locking hooks.

19. In a locking switch, the combination of a pivot clip, a contact clip, a switch blade pivoted to said pivot clip for engaging said contact clip, a bracket carried by the free end of said switch blade and having a clearance opening therethrough; a sleeve of smaller diameter than said opening extending therethrough, a disk carried by each end of said sleeve for rotatably supporting said sleeve in said bracket, a spiral spring disposed around said sleeve in said bracket and connected to said sleeve and bracket, a locking hook projecting from one of said disks, said disks and sleeve being conformed to receive an operating tool and prevent rotation thereof relatively to said sleeve and disks, and stops carried by said bracket and one of said disks for preventing rotation of said sleeve relatively to said bracket.

20. In a locking switch, the combination of a pivot clip, a contact clip, a switch blade pivoted to said pivot clip for engaging said contact clip, a bracket carried by the free end of said switch blade and hav-

ing a clearance opening therethrough, a sleeve of smaller diameter than said opening extending therethrough, a disk carried by each end of said sleeve for rotatably supporting said sleeve in said bracket, a spiral spring disposed around said sleeve in said bracket and connected to said sleeve and bracket, a locking hook projecting from each of said disks, said disks and sleeve being conformed to receive an operating tool and prevent rotation thereof relatively to said sleeve and disks, and stops carried by said bracket and one of said disks for preventing rotation of said sleeve relatively to said bracket.

21. In a locking switch the combination of a pivot clip, a contact clip, a switch blade pivoted to said pivot clip for engaging said contact clip, a bracket carried by the free end of said switch blade and having a clearance opening therethrough, a sleeve of smaller diameter than said opening extending therethrough, a disk carried by each end of said sleeve for rotatably supporting said sleeve in said bracket, a spiral spring disposed around said sleeve in said bracket and connected to said sleeve and bracket, a locking hook projecting from one of said disks, said disks and sleeve being conformed to receive an operating tool and prevent rotation thereof relatively to said sleeve and disks, stops carried by said bracket and one of said disks for preventing rotation of said sleeve relatively to said bracket, a catch pivotally supported adjacent the contact clip for engaging said locking hook in the closed position of said switch blade and a spring tending to hold said catch in its locking position, the engaging surfaces of said catch and locking hook preventing rotation of said catch and locking hook under the action of said spiral spring.

22. In a locking switch, the combination of a pivot clip, a contact clip, a switch blade pivoted to said pivot clip for engaging said contact clip, a bracket carried by the free end of said switch blade and having a clearance opening therethrough, a sleeve of smaller diameter than said opening extending therethrough, a disk carried by each end of said sleeve for rotatably supporting said sleeve in said bracket, a spiral spring disposed around said sleeve in said bracket and connected to said sleeve and bracket, a locking hook projecting from each of said disks, said disks and sleeve being conformed to receive an operating tool and prevent rotation thereof relatively to said sleeve and disks, stops carried by said bracket and one of said disks for preventing rotation of said sleeve relatively to said bracket, a catch mechanism for engaging the locking hooks in the closed position of the switch blade, and a spring tending to hold said catch mechanism in its

locking position, the engaging surfaces of said catch mechanism and locking hooks preventing rotation of said catch mechanism and said locking hooks under the action of said spiral spring.

23. In a locking switch, the combination of a pivot clip, a contact clip, a switch blade pivoted to said pivot clip for engaging said contact clip, a locking member carried by 10 said switch blade and having a limited range of movement relatively to said blade, and means constantly tending to move said member toward its position limiting said range of movement, said member having an 15 aperture for receiving an operating tool to move said blade toward and away from said contact clip, whereby said operating tool restrains said moving means and is held in engagement with said member during motion of said blade toward and away from 20 said contact clip.

24. In a locking switch, the combination of a pivoted switch blade having open and closed positions, a locking member carried 25 by said blade having locking and releasing positions, and means tending to move said member to its locking position, said member having an aperture for receiving and engaging a switch operating tool constituting the only restraining means for 30 said moving means during movement of said blade to either its open or its closed position, whereby said engagement between

said member and tool moves said member to its releasing position during both movements of said blade.

25. In a locking switch, the combination of a pivoted switch blade having open and closed positions, a locking member pivotally carried by said blade and free to rotate relatively to said blade during movement of the latter from either of its positions to the other, and means tending to rotate said member to its locking position, said member having an aperture for receiving and engaging a switch operating tool to restrain said moving means and said engagement between said member and tool preventing movement of either said member or said tool relatively to the other of said 50 parts during movement of said blade to either its open or its closed position.

26. In a locking switch, the combination of a pivoted switch blade, a locking member pivotally carried by said switch blade, 55 and means tending to rotate said member to its locking position, said member having an aperture for receiving and engaging a switch operating tool, said aperture and tool being conformed to prevent relative motion between said member and said tool during movement of said switch blade.

In witness whereof I hereunto subscribe my name this 3rd day of April, A. D. 1918.

EDSON O. SESSIONS.
